ALEXANDER CHRISTOPHER WUNSCH, OF WINNIPEG, MANITOBA, CANADA.

WATER-MOTOR.

1,083,975.

Specification of Letters Patent.

Patented Jan. 13, 1914.

Application filed December 16, 1912. Serial No. 736,987.

To all whom it may concern:

Be it known that I, ALEXANDER CHRISTOPHER WUNSCH, of the city of Winnipeg, in the Province of Manitoba, Canada, have invented certain new and useful Improvements in Water-Motors, of which the following is the specification.

My invention relates to a water motor, and the object of the invention is to provide an inexpensive, durable and efficient motor which can be quickly connected up for use and which cannot stop in any dead or central position once the water is turned on.

It consists essentially in an inclosing casing containing a valve casting supplied with suitable ports, an outlet pipe communicating with the valve receiving casting, a valve mounted in the casting supplied with an inlet port and two outlet ports, a feed pipe communicating with the inlet port of the valve, a drive spindle rotatably mounted in the casing, a wing or vane secured to the spindle and operating within the casing, pins extending from the base of the valve, and means carried by the wing or vane designed to operate the valve, the parts being arranged and constructed as hereinafter more particularly described.

Figure 1 is a plan view of the device with the top of the casing removed. Fig. 2 is an inverted plan view of the device with the bottom of the casing removed. Fig. 3 is a vertical cross sectional view centrally through the casing, the section being taken in the plane denoted by the line X X', Fig. 2. Fig. 4 is a side elevation of the motor as it appears in use. Fig. 5 is a horizontal sectional view through the valve receiving casting and the valve. Fig. 6 is a side elevation of a portion of the vane and parts carried thereby. Fig. 7 is a cross sectional view through the bolt supporting one of the valve actuating arms, the section being taken in the plane denoted by the line Y Y', Fig. 6. In the drawings like characters of reference indicate corresponding parts in each figure.

1 represents a casing formed from a cylindrical shell 2 closed by a top piece 3 and a bottom piece 4, these parts being held to the shell by removable bolts 5. The top and bottom pieces are fitted with bosses 6 and 7 which receive a tubular shank 8 rotatably, the upper end of the shank being closed by a cap piece 9 screwed into the boss 6.

10 is a stuffing box threading into the boss 7 and receiving the shank.

11 is a spindle entering the shank and releasably secured to the same by a set screw 12. The spindle is actually the driving spindle of a washing machine 13 or other similar device.

14 is a valve receiving casting located within the casing between the shell and the shank, which casting is permanently secured to the shell and bottom 4 of the casing and has the sides radiating from the shank. The casting is cored out centrally to receive a hollow cylindrical valve 15 which fits snugly between the top and bottom of the casting and is fitted with an inlet port 16 and two further independent ports 17 and 18. The inlet port opens at 19 and 20 to the outer face of the valve and these openings as well as the ports 17 and 18 are designed to register at proper instants and in a set manner with further ports 21 and 22 supplied on the casting 14. The top of the casting is supplied with an opening 23 which communicates continuously with the inlet port 16, the valve and with the inlet water pipe 24 carried by the casing.

25 is an outlet water pipe secured to the casing and communicating directly through the bottom 4 thereof with the hollow interior 15' of the valve.

26 and 27 are two actuating pins extending from the lower end of the valve into the interior of the casing, it being noticed that the lower end of the casting 14 is notched 28 away at 29.

30 is a vane or wing radiating from the spindle and engaging with the shell and the top and bottom of the casing. The vane is fixed to the spindle in any suitable way and is supplied with a packing piece 31 which insures a water-tight joint with the shell and the top and bottom of the casing. This vane actually divides the casing into two compartments "A" and "B" at all times, the compartments varying in size depending on the position of the vane and appearing between the opposite face of the vane and the opposite face of the valve casting.

32 and 33 are pairs of opposing lugs formed on each side of the vane and receiving bolts 34 which carry valve actuating arms 35 and 36 respectively. The arms are swung on the bolts and are fitted at their extremities with downwardly directed pins 37.

and have the body portions thereof notched away at 38, the object of which will be later described.

5 Spiral springs 39 encircle the bolts and have their upper ends tied at 40 to the top lugs 32 and their lower ends passed into suitable openings located at 41 in the arms. The springs are wound so as to retain the arms normally in a set position in respect to the vane.

42 and 43 are pins extending upwardly from the bottom 4 of the casing, which pins are located in a particular position so as to engage with the arms 35 and 36.

15 44 is a packing strip carried by the casting and bearing on the spindle.

I will now describe the operation of the device, reference being had particularly to Figs. 1 to 5 of the drawings and assuming that running water (under pressure) is admitted to the valve through the pipe 24.

The water enters the port 16 and is admitted through the opening 20 and the duct 22 to the interior of the casing, it being noticed that at this time the opening 19 is not registering with the port 21. The water accordingly forces the vane around in the casing until the arm 35 engages with the pin 43 and as the vane continues turning the said arm is formed inwardly toward the vane by the pin with the result that the outer end thereof carrying the pin 37 is passed behind the valve actuating pin 26. Shortly after this occurs the arm 35 is freed

35 from the pin 43 through the notched away portion 38 so that the arm 35 is freed to swing in the direction indicated by the arrow, Fig. 1, acted upon by the spring 39. It accordingly carries the actuating pin 26 with it
40 and turns the valve to a position which

13 and turns the valve to a position which causes the opening 19 to register with the opening 21 and the opening 18 to register with the opening 22. When this occurs the on-coming water passes in an opposite direction into the casing and rotates the vane back to the original position, the water in front of the valve escaping freely through the opening 22 and port 18 to the outlet

50 the arm 36 co-acts with the pin 42 and arm 27 to reverse the valve in a like manner to that just described and this reversing of the valve continues as long as water under pressure is allowed to flow through the pipe 24.

55 into the port 16. Accordingly the spindle 11 is oscillated backwardly and forwardly. It will be seen that there is no possibility of the motor refusing to operate as there are no dead center positions as is common in 30 some motors of which I am aware.

What I claim as my invention is:—

1. A water motor comprising an inclosing casing, a tubular centrally disposed shank rotatably mounted in the casing, a
65 spindle releasably secured to the shank a

permanent valve receiving casting located within the casing and extending between the shank and the inner wall of the casing, said casting being provided with a hollow interior and having side ports therein, a hollow cylindrical valve rotatably mounted in the valve receiving casting and having a pair of openings in the outer face thereof communicating with a common inlet port located in the body of the valve and provided further with an opposing pair of ports passing from the exterior to the interior thereof, the latter opening and ports being designed to register with the ports aforesaid in the valve receiving casting upon the valve being turned, a feed pipe connected with the casing and communicating through a suitable opening reserved within the casing with the feed port aforesaid in the body of the valve, an outlet pipe secured to the casing and communicating with the hollow center of the valve, a vane secured to the spindle and engaging with the inner wall of the casing, spring pressed actuating arms extending from the opposite sides of the vane, said arms having portions thereof notched away, suitably located permanent pins carried by the casing and engageable with the actuating arms and actuating pins extending from the valve freely through the valve casting into the interior of the casing, said pins being engaged alternately by the respective actuating arms, as and for the purpose specified.

2. A water motor comprising an inclosing 100
casing, a tubular centrally disposed
shank rotatably mounted in the casing, a
spindle releasably secured to the shank, a
permanent valve receiving casting located
within the casing and extending between 105
the shank and the inner wall of the casing,
said casting being provided with a hollow
interior and having side ports therein, a
hollow cylindrical valve rotatably mounted
in the valve receiving casting and having 110
a pair of openings in the outer face thereof
communicating with a common inlet port
located in the body of the valve and pro-
vided further with an opposing pair of ports
passing from the exterior to the interior 115
thereof, the latter opening and ports being
designed to register with the ports aforesaid
in the valve receiving casting upon the valve
being turned, a feed pipe connected with
the casing and communicating with the inlet 120
port, a reciprocating vane secured to the
spindle and engaging with the inner wall
of the casing, said vane dividing the casing
into two compartments located on opposite
sides of the valve casting, actuating pins ex- 125
tending from the valve freely through the
valve casting into the respective compart-
ments, spring pressed pivotally mounted
arms extending from the opposite sides of
the vane and designed in the reciprocation 130

of the vane to pass into the paths of the pins, and means engageable alternately in the reciprocation of the vane with the respective actuating arms designed to engage 5 with and then release the arms to strike the pins and turn the valve, as and for the purpose specified.

Signed at Winnipeg, this 31 day of January, 1912.

ALEXANDER CHRISTOPHER WUNSCH.
